United States Patent Office

Des. 223,983
Patented June 27, 1972

223,983

PAIR OF FLEXIBLE GOGGLES

George H. Schauweker, Southbridge, Mass., assignor to
American Optical Corporation, Southbridge, Mass.

Filed Sept. 16, 1970, Ser. No. 25,024

Term of patent 14 years

Int. Cl. D2—03

U.S. Cl. D2—234

FIG. 1

FIG. 2

FIG. 3

FIG. 4

FIG. 1 is a perspective view of a pair of flexible goggles showing my new design;

FIG. 2 is an enlarged front elevational view thereof;

FIG. 3 is an enlarged top plan view thereof;

FIG. 4 is an enlarged side elevational view thereof.

The side not shown is substantially the same in appearance as the side shown.

The strap is fragmentarily shown in FIGS. 3 and 4 for convenience of illustration.

I claim:

The ornamental design for a pair of flexible goggles, substantially as shown and described.
